SECTIONAL COMMEMORATIVE TABLET

Albert J. Lytle, Waterloo, Iowa

Application April 23, 1934, Serial No. 721,863

5 Claims. (Cl. 40—63)

My invention relates to improvements in commemorative wall tablets, and the object of my improvement is to supply a device of this class assembled from sections added from time to time 5 to one or more end plates in any desired number and sequence.

Another object of my improvements is to so connect said plates and tablet sections removably and rigidly together and so as to place them in 10 a single plane relation.

Another object of my improvements is to shape and arrange the connecting means therefor in a way to permit the device to be mounted upon a supporting wall in a closely abutted parallel relation thereto and to be secured thereto releasably 15 yet permanently.

Another object of my improvements is to effect a combination between such assembled sections and header end plates, whereby data entered upon the former may be related to other data or inscriptions or symbols on one or both end plates.

Another object of my improvements is to furnish special hanging and securing means for the end plates to mount them upon a wall surface, in a 25 convenient, durable manner, which will also permit them to be disassembled in any number from the securing means when desired, as in adding other sections thereto or effecting a rearrangement of the sections and header plates.

These objects I have accomplished in actual 30 reduction to practice by the means which are hereinafter described and claimed, and which are illustrated in the accompanying drawing, in which Fig. 1 is a front elevation of my invention as completely assembled, and Fig. 2 is a side or 35 edge elevation thereof, partly in elevation and partly in vertical section.

My invention is particularly designed and intended for use as a permanent memorial tablet, 40 whose headers and assembled sections therebetween may have thereon related inscriptions or symbols upon the headers, with inscribed names having other or related data upon the sections, as will be described hereinafter, and which may be also varied in other ways without departing 45 from the invention, as the appended claims will cover mechanical equivalents or changes in any of the parts thereof as partly or wholly assembled together.

The numerals 1 and 6 denote respectively the 50 top and bottom header plates of my invention, and the numeral 5 denotes each of a plurality of elongated flat oblong sections as assembled together with their abutting upper and lower edges 55 connected releasably together and with the front

faces of all these headers and the interpolated sections in any desired number preferably in a single plane. However these headers, or the sections, may be otherwise shaped, or having their respective front faces in other than a single plane or otherwise arranged relatively to each other, or may be positioned in a horizontally or otherwise directed series, without thereby departing from this invention.

The top header plate 1 may have its side and 10 top edge shaped ornamenteally peripherally, the drawing showing in Fig. 1 a simple ornamental shape having a top semicircular projection 2 upon which may be shown a symbol 15 3 or other device or inscription, and the main body of the plate may bear any kind of inscription 4 desired, or bearing some relation in meaning to the symbol 3.

While the rectangular sections 5 are shown 20 as of the same shape and size, they also may be varied in these regards, while preserving otherwise their mechanical assembled relation to each other and to the top and bottom header plates 1 and 6 according to this invention.

The bottom header plate 6 may also be varied in 25 size and shape, as in ornamentation, and may have an inscription thereon, as denoted at 7, which may relate in meaning to the inscriptions upon the top header plate 1 and to those upon the sections 5.

Particularly, the invention may be used as a 30 commemorative tablet to be mounted upon a building or other structure, as to be a memorial to deceased members of a society or brotherhood, whereby the names of other such members may 35 be added from time to time, by the addition for each of another section 5, to the preceding plurality of sections.

Referring to said Fig. 2, each section 5 has an 40 integral apertured lug set off at the rear at 8 and projecting upwardly near each end to overlap the abutting rear surface of the section above, or the header plate 1, and the overlapped parts are provided with aligned holes threaded to receive a header flush screw 9.

By this means the header plates and immediately assembled sections 5 are all in a single tier, front faces in one plane and the rear faces of the lugs 8 in a single parallel plane, so that the device may be mounted flatly upon a wall 50 face as a structural element thereof permanently, and without projecting parts forwardly, and with all the lugs bearing against the wall.

Any suitable means may be used for releasably mounting the device upon a supporting 55

structure, other than that shown. The numeral 10 denotes screws fitted in threaded holes in or near the corners of the pair of header plates 1 and 6 and for insertion in the supporting structure, and the numeral 11 denotes headed ornamental plugs having a short stem in each case fitted into the forward part of each said screw hole in advance of the headless screw 10 therein. These headed elements 11 thus serve 10 as ornamental bosses.

The assemblage of headers and sections is rigid with tight fitting joints, and other sections may be added after removing either header plate.

I claim:

- 15 1. A device of the class described, comprising in combination, header plates spaced apart for carrying insignia or inscriptions, and a plurality of like filler plates therebetween for receiving inscriptions and alined therewith with their inscription receiving faces in a single plane, and with abutting edges, and clamping and screw means for separably connecting said elements together.
- 20 2. A device of the class described, comprising in combination, header plates spaced apart for carrying insignia or inscriptions, a plurality of filler plates therebetween for receiving inscriptions and alined therewith with their inscription receiving faces substantially in a single plane and with abutting angle props in the rear with their rear faces in a single plane, means for separably rigidly connecting said elements together, and other means for fastening the device upon a supporting structure.
- 30 3. A device of the class described, comprising in combination, header plates spaced apart for carrying insignia or inscriptions, a plurality of like filler plates rigidly separably assembled and fitted to each other between and to said header plates, with their front faces alined in one plane,

and angular seating and fastening means for securing said elements together in a rigid upright assemblage releasably, permitting addition of other filler plates to the assemblage or subtraction of the plates therefrom from time to time.

4. A device of the class described, comprising in combination, header plates, a plurality of rectangular inscription receiving filler plates with engaging joints between them and between certain of them and the header plates, the front faces of all the plates being in alinement, all the plates being apertured, each of the plates below the top header plate having rearwardly offset lugs projecting upwardly to contact with the rear face of the plate above, said lugs being apertured with apertures registering with the apertures of the plates above, and screw fastening means removably seated in said alined apertures to connect the overlapped plates and lugs together rigidly, the rear faces of the lugs being in the same plane, and the ends of said fastening means flush respectively with the front faces of the plates and with the rear faces of the lugs.

5. A device of the class described, comprising in combination, a plurality of inscription receiving elements assembled in a congeries and rigidly separably secured together at abutting edges to present their front faces in a common plane, whereby additional inscription receiving elements may be assembled therewith from time to time, certain of the elements having offset rear lugs contacting with overlying abutting elements with the rear faces of the lugs in the same plane, and means for separably rigidly connecting said lugs to the contacting elements at interlocked joints.

ALBERT J. LYITLE. 40
